(57) **CLAIM**

The ornamental design for a filter bowl, as shown and described.

DESCRIPTION

FIG. 1 is a front exploded perspective view of a filter bowl, showing my new design;

FIG. 2 is a rear exploded perspective view thereof;

FIG. 3 is a front exploded view thereof;

FIG. 4 is a rear exploded view thereof;

FIG. 5 is a left exploded side view thereof;

FIG. 6 is a right exploded side view thereof;

FIG. 7 is a top exploded view thereof;

FIG. 8 is a bottom exploded view thereof; and,

FIG. 9 is a top combined view thereof.

The broken lines in the drawings illustrate the portions of the filter bowl, which form no part of the claimed design.
